APPARATUS FOR WASHING THREADS WOUND ON BOBBINS

Filed Jan. 12, 1928

FIG. 1.

FIG. 2.

Rudolf Haas, Inventor
by Mach. Bldng. Attorneys

UNITED STATES PATENT OFFICE.

RUDOLF HAAS, OF BADEN-BADEN, GERMANY.

APPARATUS FOR WASHING THREADS WOUND ON BOBBINS.

Application filed January 12, 1928, Serial No. 246,158, and in Germany January 21, 1927.

German Patent No. 229,284 dated 27th October, 1927 discloses a particularly effective method of washing threads, especially artificial silk threads, wound on perforated 5 bobbins, which consists in causing air and/or gases and/or vapours together with a washing liquid to penetrate through the layers of wound threads.

The present invention has for its object 10 to provide effective apparatus for carrying out of the method referred to.

According to the invention, a rotatable frame is provided upon which the bobbins to be washed are arranged in such manner 15 that on rotation of the frame the bobbins are periodically and intermittently subjected to the action of the washing liquid, the interiors of the bobbins being connected to a suction pipe so that the washing liquid 20 as well as the surrounding air and/or gases and/or vapours may be drawn through the layers of threads.

The suction pipe is conveniently connected with a central part of the frame, by means 25 such as a stuffing box, so that it may remain stationary whilst the frame rotates.

The bobbins, which are constructed so as to be permeable, may be arranged in any suitable manner, for example, singly, upon 30 the frame. They may, however, be suitably arranged in groups, by stringing them in a manner known per se on rods or tubes with the interposition of packing rings. These 35 groups are fixed upon the frame, suitable means being employed for spacing the groups apart. Thus the groups may be arranged radially—i. e. in the form of a star—or parallel to the axis—i. e. cylindrically—or in the form of a cone or in any 40 other suitable manner. In a particularly effective arrangement, groups of bobbins strung upon suitable tubular supporting rods or tubes are arranged so that the groups are disposed obliquely around the axis of 45 the frame whereby the individual groups of bobbins constantly change their angular position with respect to horizontal planes. This results in the practical advantage, that by choosing the correct direction and speed 50 of rotation, the liquid drawn through the layers of threads may be caused to flow away laterally.

A simple constructional arrangement consists in rotatably mounting upon a horizontal 55 or sloping axis, a chamber provided at

the centre of one side with a connection to a vacuum pipe, and on the other side with obliquely disposed connections for groups of bobbins arranged, for example, substantially in the form of a hyperboloid. 60

The liquid penetrating through the bobbins into the chamber can be drawn off by means of a siphon or by means of scoops or the like. Opposite to the chamber a single support for the outer ends of the groups of bobbins for example in the form of a disc with notches or perforations can be arranged. In place of this a second similar chamber may be provided. 65

The movement of the frame, especially 70 its rotation, may be uniform or intermittent, slow or rapid, in any case such as is most suitable for the periodic action of the washing liquid.

The washing liquid may be placed in a 75 trough underneath the frame, the bobbins dipping into the liquid once at every revolution. The periodic moistening of the bobbins, can, however, be effected in other ways, for example by irrigating or by spraying. 80

A suitable construction of apparatus is illustrated, by way of example, in the accompanying drawing in which Fig. 1 is a sectional elevation and Fig. 2 is a cross-section 85 near the vacuum chamber. Fig. 3 is a section through the suction or vacuum chamber.

The vacuum chamber is mounted on the shaft *a*, which is carried in the supports *b* and is rotated by the belt drive *c*. In the 90 centre of the chamber there is an opening for the suction pipe *f* packed by the stuffing box *e*. This suction pipe *f* is bent downwards in the interior of the chamber *d*, so that it siphons off the washing liquid flowing into the chamber. On the outside of the chamber obliquely disposed support connections *g* are provided, on which the groups of bobbins *h*, are strung, said bobbins being arranged end to end with the 95 interposition of packings *i*. At their other end the groups of bobbins are supported in a disc *k* provided with suitable recesses, while, if necessary, the groups can be pressed against the chamber *d*, by suitable means 100 (not shown). The whole frame rotates over the trough *l* containing the washing liquid. Owing to the oblique positions of the groups of bobbins as they leave the trough, the 105 washing liquid is enabled to flow off into 110

the chamber *d*. As shown in Fig. 3, the suction tube *f* has a liquid-tight packing *e*. Likewise, the supports *g* are tubular.

I claim:—

- 5 1. Apparatus for washing threads wound on bobbins, comprising a rotatable chamber, means connecting the said chamber to a source of suction, tubular fittings upon which the bobbins with the interposition of packing, are strung end to end in groups, the said fittings communicating with the interior of the bobbins and with the interior of the said chamber and means by which the bobbins may be periodically and intermittently subjected to the action of a washing liquid and a gaseous medium such as air.
- 10 2. Apparatus for washing threads wound on bobbins, comprising a rotatable chamber upon which the bobbins are carried, tubular fittings extending from the said chamber upon which fittings the bobbins with the interposition of packing are strung end to end in groups, the said fittings communicating with the interior of the said chamber and with the interior of the bobbins and being arranged so that during the rotation of the said chamber the washing liquid entering the said bobbins flows off laterally, and means connecting the said chamber with a source of suction.
- 15 3. Apparatus for washing threads wound on bobbins comprising a rotatable element, tubular fittings carried by the said element and upon which the bobbins with the interposition of packing are strung end to end in groups, the said fittings being arranged obliquely around the axis of the said element so that their inclination with respect to horizontal planes changes constantly during the rotation of the said element, means connecting the said fittings with a source of suction, and means by which the bobbins may be periodically and intermittently subjected to the action of a washing liquid and a gaseous medium such as air.
- 20 4. Apparatus for washing threads wound on bobbins, comprising a rotatable chamber, means such as a co-axial inlet pipe connect-

ing the said chamber to a source of suction, tubular fittings communicating with the interior of the said chamber and extending from one side thereof in the form of a hyperboloid, upon which fittings the bobbins with the interposition of packing are strung end to end in groups and means by which the bobbins may be periodically and intermittently subjected to the action of a washing liquid and a gaseous medium such as air.

5. Apparatus for washing threads wound on bobbins, comprising a trough containing a washing liquid, a rotatable chamber mounted upon an axis above the said trough, the said chamber dipping into the said washing liquid, tubular fittings extending laterally and obliquely from the said chamber adjacent its periphery in the form of a hyperboloid upon which fittings the bobbins with the interposition of packing are strung end to end in groups, a stationary suction pipe extending co-axially into the said chamber and bent so that its end is disposed within and adjacent the lower part of the said chamber, and means for packing the joint between the said suction pipe and the said chamber.

6. Apparatus for washing threads wound on bobbins, comprising a trough containing a washing liquid, a rotatable chamber mounted upon an axis above the said trough, the said chamber dipping into the said washing liquid, tubular fittings extending laterally and obliquely from the said chamber adjacent its periphery in the form of a hyperboloid, upon which fittings the bobbins with the interposition of packing are strung end to end in groups, a stationary suction pipe extending co-axially into the said chamber and bent so that its end is disposed within and adjacent the lower part of the said chamber, means for packing the joint between the said suction pipe and the said chamber, and means for supporting the outer ends of the said tubular fittings.

In testimony whereof I hereunto affix my signature.

RUDOLF HAAS.
